UNITED STATES PATENT OFFICE.

HENRY C. REUTER, OF CHICAGO, ILLINOIS.

STORE-FRONT CONSTRUCTION.

Application filed November 23, 1927. Serial No. 235,269.

This invention relates to store front constructions preferably made of bronze or other suitable metal which is strong and durable and which does not require reinforcement to maintain it in its intended form.

The invention relates more particularly to ventilator constructions or parts hingedly mounted to rigid or fixed portions of the store front construction to permit of the swinging 10 of said first mentioned parts to open or closed positions, as well as to the features of construction embodied in the parts of the store front surrounding the hinged or swinging member.

Another object of the invention is to provide a frame construction for efficiently holding a window pane, and means for connecting said frame to store constructions already in use as well as to new installations. The advantages of the invention will be more fully understood as I proceed with my specification, from which it will be seen that it is frequently necessary, in order to provide ventilation, to remove fixed glass panes from 20 store fronts and to reset the same in frames which are to be hingedly attached to the parts which originally held the window pane. The means which I have provided for adapting that portion of the store front in which 25 the original pane was mounted to receive the reset pane frame is an important feature of my invention in repair or alteration work.

In the drawings:

Figure 1 is a front elevation, broken away, 30 of a part of a store front embodying my invention.

Figure 2 is a vertical sectional view taken in the plane of the line 2, 2, of Figure 1, looking in the direction indicated by the arrows, 40 but showing both the upper and lower part of the construction of which Figure 1 illustrates only one portion.

Figure 3 shows part of the construction of Figure 2, with the pane and its frame in 45 pivoted position.

In that embodiment of my invention shown in the drawings, I have chosen to illustrate my invention as applied to a construction wherein a vertically disposed window frame 50 is made to swing about a horizontal pivot located at the top thereof, and the movable parts are adapted to swing inwardly. It is obvious that the parts may be reversed so that the window pane and frame will swing

outwardly; and if desired, the hinge or 55 pivotal connection may be at the bottom of the window frame.

The masonry or other fixed support of the building or store front is indicated at 5 and connected thereto is a fixed metal frame such 60 as has heretofore been used for receiving a glass pane. This metal frame comprises an inner or rear wall 6, having an outwardly directed flange 7 at one end, and integral at its other end with a wall 8, extending at 65 right angles thereto. The wall 8 is integral with an outer wall 9, which may be of any desired shape to fit the particular installation. That is to say, the wall 9 may constitute a side post, corner post, or the top or bottom 70 frames.

When used originally to receive a glass pane, the flange 7 of the metal frame was in engagement with the rear surface of a pane of glass, the latter being held in place by the 75 retaining member comprising walls 10, 11 and 12, said retaining member being removably secured to the wall 8. The wall 12 of the retaining member was intended to contact with the front surface of the glass pane. 80 A construction such as described, wherein the pane is held in place between the flange 7 and the wall 12 of the retaining member is shown and described in my prior Patent, No. 1,589,560.

When it is desired to alter a construction 85 of the type described, to permit the pane and a frame therefor to swing with respect to the rest of the store front construction, the arrangement about to be described is exceedingly efficient to produce a neat connection:— 90 First, the pane is removed and a pane 13 of proper size provided. This pane 13 is set into a frame comprising integral walls 14, 15 and 16, the walls 14 and 16 being parallel to each other and connected together intermediate 95 their ends by the cross wall 15. One end of each of said walls 14 and 16 is provided with pane engaging flanges, 17 and 18, respectively, for engaging the pane surfaces. The edge 100 of the pane is spaced apart from the wall 15 by a rubber strip or other cushioning means 19.

Between the pane holding frame and the 105 fixed parts 6, 7, I provide an intermediate member constructed as follows: A strip of metal rolled longitudinally or otherwise formed into a substantially H-shaped mem-

ber, comprising walls 20 and 21, connected together between their ends by the cross wall 22; the wall 20 having an angle bar extension 23, 24, at that end toward the frame member 14. In assembling the parts (the retaining member comprising the walls 10, 11 and 12, having been removed), the H-shaped connecting member is placed into position with its wall 21 in contact with the wall 6 and flange 7, and then the retaining member is replaced, with its wall 12 against the wall 20 of the intermediate strip, and the parts connected together by a screw bolt 25 passing through registering apertures in the walls 10, 12, 20, 21 and 6. Thereafter the pane frame comprising the walls 14, 15 and 16, is placed into position with the flanged side of the wall 14 contacting with the inner surface of the wall 24 of the intermediate member, and the end of 20 the wall 16 contacting with the flanged side of the wall 21. In this position, the leaves 26 and 27 of a hinge are secured to the walls 16 and 6, respectively to connect the pane frame to the fixed member. 25 From the foregoing, it will be understood that the construction described is efficient for its intended purpose, whether applied to a new installation or used in connection with store fronts already installed. In the latter use it 30 may readily be connected to a fixed part of the construction without alteration thereof. The intermediate H-shaped member bridges the gap between the hingedly connected parts and affords a tight closure between the movable and fixed structures, three points of contact, having air gaps between them, being provided. I refer to the contact of the flanged side of the wall 14 with the inner surface of the wall 24; the contact between the flanged side of the wall 24 with the outer surface of the wall 14; and the contact between the flanged side of the wall 21 with the wall 16. 35 The appearance of the construction is attractive when the ventilator section is in either its open or closed position, and when closed, the engagement between the parts is firm and dust and moisture proof. 40 Ventilating apertures 28, which permit moisture and foul air to escape are provided in the walls 10, 12 and 22, particularly at the bottom of the window construction. 45 A bracket 29 for holding the slideable locking bolt 30, and a keeper member 31, may be connected to the walls 16 and 6, respectively, at that side of the window frame opposite the hinged connections, to permit the window frame to be locked to the fixed support. 50 I claim as my invention:

1. In a store front construction, a fixed metallic frame surrounding a window opening and having spaced pane receiving portions, a pane carrying frame hingedly connected to the fixed frame, and an intermediate member removably secured between trans-

verse portions of the fixed frame and engaging the pane carrying frame when the latter is in closed position.

2. In a store front construction, a fixed metallic frame surrounding a window opening and having spaced pane receiving portions, a pane carrying frame hingedly connected to the fixed frame, and an intermediate member comprising two spaced apart connected walls removably secured between transverse portions of the fixed frame and engaging the pane carrying frame when the latter is in closed position.

3. In a store front construction, a fixed metallic frame comprising adjustably connected, spaced apart walls, a pane carrying frame hingedly connected to the fixed frame, and an intermediate member removably secured between the connected walls of the fixed frame comprising spaced apart walls each engaging said fixed frame and pane carrying members.

4. In a store front construction, a fixed metallic frame, a removable retaining member adjustably connected thereto, a pane carrying frame hingedly connected to the fixed frame, and an intermediate member adapted to be rigidly secured to the fixed frame and the retaining means, and having spaced apart extensions contacting with the pane carrying frame when the latter is in closed position.

5. In a store front construction, a fixed metallic frame, a removable retaining member adjustably connected thereto, a pane carrying frame hingedly connected to the fixed frame, and an intermediate member adapted to be rigidly secured to the fixed frame and the retaining means, and having spaced apart flanged extensions adapted to contact at a plurality of points with the pane carrying frame when the latter is in closed position.

6. In a store front construction, a fixed metallic frame comprising adjustably connected, spaced apart walls providing an outwardly facing pane receiving channel therebetween, a pane carrying frame comprising a plurality of spaced apart walls, one of which is hingedly connected to one wall of the fixed frame, an intermediate member located in the channel and connected to the fixed frame member and having flanged walls adapted to contact with the spaced apart walls of the pane carrying frame.

7. In a store front construction, a fixed metallic frame comprising adjustably connected, spaced apart walls providing an outwardly facing pane receiving channel therebetween, a pane carrying frame comprising a plurality of spaced apart walls, one of said walls being hingedly connected to one wall of the fixed frame, an intermediate member comprising spaced apart walls located in the channel and connected to the fixed frame member, flanges on said walls adapted to

contact with the spaced apart walls of the pane carrying frame, and a flange on one of the pane carrying frame walls for contacting with one of the intermediate member walls between the side edges thereof.

8. In a store front construction, a pane carrying frame comprising spaced apart walls and hingedly connected to a support, a member substantially H-shaped in cross sec-

tion connected with the support and extending forwardly of the hinged connection to be in contact with the pane carrying frame when the latter is in closed position.

In testimony that I claim the foregoing as my invention I affix my signature this 15th day of November, 1927.

HENRY C. REUTER.
